UNITED STATES PATENT OFFICE.

ALEXANDER HALLIDAY, OF PRINCE RUPERT, BRITISH COLUMBIA, CANADA.

CRUSHER FOR MINERAL ORES.

Application filed May 31, 1922. Serial No. 564,874.

To all whom it may concern:

Be it known that I, ALEXANDER HALLIDAY, of the town of Prince Rupert, in the Province of British Columbia, Canada, have invented certain new and useful Improvements in Crushers for Mineral Ores, of which the following is the specification.

My invention relates to improvements in mineral separators and the object of the invention is to devise a complete unit which is simple in construction whereby all the operations necessary in carrying out the process of separating precious metals from ores may be performed, such as the crushing, treating and passing through quicksilver and oil and which will perform these operations with a minimum amount of power and it consists essentially of the arrangement and constructions of parts as hereinafter more particularly explained.

Fig. 1 is an end view of my crusher.

Fig. 2 is a transverse section taken intermediate the longitudinal length of the crusher.

Fig. 3 is a longitudinal section through the pulp cylinder showing the crushing roller in full.

Fig. 4 is a plan section on line 4—4, Fig. 1.

Fig. 5 is a longitudinal section through one of the flotation cylinders.

Fig. 6 is a sectional view showing one of the pulp cylinder doors.

Fig. 7 is a view of the pulp cylinder doors in elevation looking from the inside of the cylinder.

Fig. 8 is a perspective view of the flotation cylinder having the wall broken away to exhibit the interior construction.

In the drawings like characters of reference indicate corresponding parts in each figure.

1 indicates a pulp or crushing cylinder which is open at each end and is provided with a pair of internal annular flanges 2 located at each end of the cylinder. The flanges 2 are spaced apart to form an annular channel for a purpose which will hereinafter appear. 3 is a crushing roller mounted upon a shaft 4 which is journalled in a spring bearing 5 carried on a suitable supporting structure.

The spring bearing 5 is provided in order that the crushing roller will exert a yieldable pressure to permit of the rising or falling of the roller according to the size of the material to be passed beneath the same. 6

is one of the pair of doors riding freely in the channel formed by the spaced apart flanges 2. The doors are maintained in a stationary position in the channel as the cylinder revolves. The doors 6 are shown in detail in Figs. 6 and 7. In these figures 7 is the outer covering plate having a screen 8 covering the aperture 8^x extending horizontally across the plate 7 as clearly indicated by full lines in Fig. 1 and by dotted lines in Fig. 7. 9 is a lip which is attached to the plate 7 so as to extend along the lower edge of the opening 8 and is provided for discharging the fines from the pulp cylinder 1.

10 is an inside covering plate forming part of the door 6 and which is connected to the outer covering plate 7 by an annular rim 11. 12^x is an aperture formed in the plate 10 at one side of the shaft 4. 12 is a screen for the aperture 12^x. 13 is a small opening adjacent to the opposite side of the plate 10 to the opening 12^x for the purpose of returning the oversized ore which has passed the screen 12 but is too large to pass through the screen 8. 14 is a slotted aperture formed in the centre of the cover plates 7 and 10 to permit of the yielding movement of the crushing cylinder and the shaft 4 in the spring bearing 5. 15 is a pipe which passes through the door 6 and forms means for discharging the quicksilver from the cylinder 1.

16 is a launder (see Fig. 3) by which the ore is conducted to the centre of the cylinder 1 to be discharged under the crushing roller 3. 17 is a double jet connected to one of the hydraulic service pipes to circulate the pulp which passes under the crushing roller 3 by water pressure towards the outer ends of the cylinder 1. 18 is a plurality of jets discharging a stream of water to circulate the pulp transversely across the ends of the cylinder towards the crushing side of the roller.

19 is a plurality of jets for circulating the pulp in front of the crushing roller. 20 represents a tray extending around both ends and one side of the pulp cylinder 1 and which forms a channel extending under the lip 9 of the door 6, the channel being provided with closed ends as indicated at 21. The tray portion running lengthwise of the cylinder is formed with one vertical side only the bottom being turned downward at one edge to form a lip running parallel to

the side of the cylinder 1 and adjacent thereto as indicated at 22 to allow for the feeding of the pulp which has passed through the door 6 to be distributed evenly against the side of the pulp cylinder 1 for a final grind between it and the flotation cylinder 23 hereinafter described.

23 and 24 are a pair of flotation recovering cylinders of similar construction with the exception that the cylinder 24 is provided with a pair of annular flanges 25 located at each end thereof and against the edge of which the pulp cylinder bears to provide a space between the outer peripheries of the cylinders 1 and 24. The cylinders 23 and 24 are each mounted on a plurality of spiders 26. 27 are a pair of shafts journaled in bearings in a suitable supporting structure and to which the spiders 26 of the cylinders 23 and 24 are keyed.

The shafts 27 are rotated by a suitable gearing and in such a manner that both the cylinders 23 and 24 revolve in the same direction. The cylinders 23 and 24 are each provided with a pair of annular internal flanges 28 adjacent their ends to form a channel similar to that described in connection with the pulp cylinder 1. 29 are half doors semi-circular in form and fitting freely within the channels formed by the flanges 28. The doors 29 hang in a stationary position so that the cylinders 23 and 24 revolve therearound.

30 are short lengths of pipe or plugs for the purpose of discharging the contents of the cylinders 23 and 24. 31 are hydraulic jets discharging a stream of water under pressure inwardly within the flotation cylinders to agitate the contents. 32 is a wood lining preferably of barrel formation supported upon the spiders 26 of the flotation rollers 23 and 24 such lining being formed by two members 32^x and 32^y separated apart at their longitudinal centre as indicated at 33. 34 are a plurality of rifle plates which may be of any desired material and shape, and which are driven into the wood lining 32 in rows and set with the points directed substantially towards the longitudinal centre of the lining 32.

35 represents a plurality of wire guides held taut between the opposite ends of the lining 32, each pair having its ends positioned within an arc of approximately ninety degrees of the lining 32. 36 is a skimmer preferably of wood, slidably mounted upon each pair of guide wires each skimmer being provided with a pair of apertures 37 therein slightly larger than the diameter of the wires 35.

The skimmers 36 are so positioned with their guides that they work from end to end of the lining 32 by contact with the liquid inside the cylinders in a similar manner to the operation of a cable ferry, and

on the further rotation of the cylinders and the lifting of the skimmers to near the top of the cylinders they fall by gravity to the opposite end of the guides. 38 indicates a flat tray running lengthwise between the cylinders 23 and 24, the longitudinal edges of which are splayed as at 39 to form a relatively tight joint between the trays and the outer surface of the cylinders 23 and 24.

The outer ends of each tray 38 are provided with suitable rims and an outlet connection 40 to discharge into either of the cylinders as desired and as shown by pipes 41 and 42. 43 are trays suitably supported and extending beyond the end of each of the flotation cylinders 23 and 24 and into which trays the cylinders dip. 44 is a wiper located on one side of each of the trays 43 formed of rubber or any other suitable material and is similar in construction to that of the ordinary window cleaning wiper. The wipers 44 serve to wipe off the outer surface of the flotation cylinders.

45 is a water vat over which the entire crusher is placed and into which the agitating water used in the various cylinders is allowed to fall and from whence the water supply is pumped by any suitable means, not shown, for supplying the various agitating jets within the cylinders.

Having described the principal parts involved in my invention I will now briefly describe the operation of the same.

It will be noticed from the foregoing that the cylinder 1 rides and rotates upon the outer surface of the cylinder 23 and upon the annular flanges 25 of the cylinder 24 whereby a slight slipping movement is obtained at the contacting surfaces due to the difference in circumference of the cylinder 23 and flanges 25 as both cylinders 23 and 24 rotate at the same speed.

The ore to be crushed is conveyed from an ore bin along the launder 16 to the middle of the cylinder 1 and is delivered onto the top surface of the crushing roller 3 which is rotated by its contact with the inner periphery of the cylinder 1, the ore passing under the roller to receive its first crush. The cylinder 1 has an amount of quicksilver running freely therein to form an amalgam of quicksilver and gold from the ore. This amalgam coats the wall of the cylinder 1 and the periphery of the roller 3. The free amalgam remains inside of the cylinder 1 and can only pass off from the outlet 15. Streams of water are projected by the jets 17, 18 and 19 to drive the ore from the back of the roller 3 around its ends and under the crushing surface.

As the pulp formed by the crushed ore is reduced in size it passes, still containing gold not taken up by the quicksilver, through the screen 12 of the aperture 12^x, the fines passing also through the screen 8 of the aper-

tures 8x. The ore which is too large to pass through the screen 8 is returned through the opening 13 into the interior of the pulp cylinder. The fines on passing from the screen 8 fall over the lip 9 into the tray 20 from which they pass into contact with the outer surfaces of the cylinders 23 and 24 which are coated with oil from the trays 43 receiving their final grind between the outer surfaces of the cylinders 23 and 1 and being simultaneously impregnated with oil.

The oil impregnated ore and some of the material still being left coarse runs back into the tray 38 from whence it is conveyed for final treatment into the flotation cylinders 23 and 24 by the pipes 41 and 42 where it is again treated with quicksilver and agitated among the riffle plates 34 by the streams of water from the jets 31 and after treatment is drawn off from the cylinders by removing the plugs 30. A certain amount of crushed ore clinging to the cylinders 23 and 24 is wiped off by the wipers 44 into the oil trays and is periodically collected and removed. It is intended to use the interior of the cylinders 23 and 24 alternately so that the crushing machine may be kept in constant use, one flotation cylinder being drained off while the ore is being treated the other the grinding operation at the exterior of the cylinder 23 being continuous. It will be understood that in the operation of the flotation cylinders, the powdered metal adheres to the riffle plates 34 from which it is periodically removed by any suitable process.

It is not necessary to describe the various methods of treating ore with quicksilver further in detail, than has been described as all methods usually adopted can be availed of in my invention irrespective of the ores to be treated.

It will thus be seen that by my invention the crusher is provided for metalliferous ores which not only crushes the material but does so continuously and the various methods of separating precious metals from the ore can be carried on simultaneously with the crushing operations so as to form one continuous process.

What I claim as my invention is:

1. In a mineral separator, a pair of rotatably mounted parallel closely adjacent recovery cylinders, a crushing cylinder mounted between the aforesaid cylinders and having rolling contact therewith to form a second ore crushing means, means within the crushing cylinder for primarily crushing the ore, and means for feeding the ore crushed within the crushing cylinder to between such cylinder and the parallel cylinders.

2. In a mineral separator, a pair of rotatably mounted parallel closely adjacent cylinders, ore recovering means located

therein, a crushing cylinder mounted between the parallel cylinders and having rolling contact therewith to form a secondary crushing means, a primary crushing means located within the crushing cylinder, and means for feeding the finer crushed ore from the crushing cylinder to between such cylinder and the parallel cylinders for second crushing and for retaining the coarser crushed ore therein for recrushing.

3. In a mineral separator, the combination of a pair of parallel rotary cylinders, ore recovering means within said cylinders, a crushing cylinder in rolling contact with the aforesaid cylinders, separating means receiving the discharge from the crushing cylinder and serving to separate the finer ore from the coarser ore, means for delivering the finer ore to the ore recovering cylinders, and means for returning the coarser ore to the crushing cylinder for recrushing.

4. In a mineral separator, the combination of a pair of parallel rotary cylinders, ore recovery means located therein, a crushing cylinder in rolling contact with the aforesaid cylinders, separating means for discharging the finer ore from the crushing cylinder to the ore recovering cylinders and for returning the coarser ore for recrushing, and means for maintaining an oil film on the outer surface of the recovering cylinders.

5. In a mineral separator, the combination of a pair of rotary parallel cylinders, ore recovering means located therein, a crushing cylinder in rolling contact with the aforesaid cylinders, separating means arranged to discharge the finer ore from the crushing cylinder to the ore recovering cylinders and to return the coarser ore for recrushing, and oil containing means in which the lower portions of the recovery cylinders are disposed to rotate.

6. In a mineral separator, a crushing device comprising an open-ended cylinder, a crushing drum located within the cylinder to contact with the lower peripheral portion thereof and onto the top of which the ore to be crushed is fed, a carrying shaft on which the cylinder and drum are mounted, an end gate for each end of the crushing cylinder, means for supporting the end gates in a stationary position, and a screening device formed in such end gates.

7. In a mineral separator, a crushing device comprising an open-ended cylinder provided with annular channels on each end, a crushing drum located within the cylinder to contact with the lower peripheral portion thereof, a carrying shaft journaled in suitable bearings and on which the cylinder and drum are supported, segmental end gates supported upon the shaft and fitting at their edge within the annular channels of the cylinder, and screening means incorporated within the end gates.

8. In a mineral separator, a crushing device comprising a crushing cylinder, a crushing drum located within the cylinder to contact with the lower peripheral portion thereof, an annular channel formed in an end of the cylinder, a segmental end gate comprising an inner and outer wall spaced apart and connected together at their peripheral edge, the outer wall having a screen opening therein extending across the centre thereof and the inner wall with a screen opening at one side of the centre of the end gate, a fine mesh screen for the screening opening of the outer wall and a coarse mesh screen for the screening opening of the inner wall, and means for returning the coarse ore entrapped between the outer and inner walls into the centre of the crushing cylinder.
9. In a mineral separator, a crushing device comprising a crushing cylinder, a crushing drum located within the cylinder to contact with the lower peripheral portion thereof, an annular channel formed in an end of the cylinder, a segmental end gate comprising an inner and outer wall spaced apart and connected together at their peripheral edge, the outer wall having a screen opening therein extending across the centre thereof and the inner wall with a screen opening at one side of the centre of the end gate, and a return orifice at the opposite side of the centre.
10. In a mineral separator, a pair of rotatably mounted parallel and closely adjacent recovery cylinders, annular exterior end flanges extending from one of said cylinders, a crushing cylinder mounted to engage with the periphery of one of the aforesaid recovery cylinders and with the flanges of the other aforesaid recovery cylinders, recovering means located within the recovery cylinders, and means for conveying the crushed ore from the outer periphery of the recovery cylinders into the interior thereof, to be acted upon by the recovering means.
11. In a mineral separator, a pair of rotatably mounted parallel and closely adjacent recovery cylinders, annular exterior end flanges extending from one of said cylinders, a crushing cylinder mounted to engage with the periphery of one of the aforesaid recovery cylinders and with the flanges of the other of the aforesaid recovery cylinders, recovering means located within the

recovery cylinders, a tray extending between the recovery cylinders and having its edges splayed to fit the exterior periphery thereof, and a pipe provided with valved branches extending from such tray into the interior of each of the recovery cylinders.

12. In a mineral separator, a pair of rotatably mounted parallel and closely adjacent recovery cylinders, annular exterior end flanges extending from one of said cylinders, a crushing cylinder mounted to engage with the periphery of one of the aforesaid recovery cylinders and with the flanges of the other of the aforesaid recovery cylinders, recovering means located within the recovery cylinders, a tray extending between the recovery cylinders and having its edges splayed to fit the exterior periphery thereof, a pipe provided with valved branches extending from such tray into the interior of each of the recovery cylinders, and suitably arranged water jets for agitating the ore within the recovery cylinders.

13. In a mineral separator, the combination with the crushing cylinder having a discharge for the crushed ore at the ends thereof, a tray extending around three sides of the crushing cylinder and having the inner edge of the longitudinally extending portion formed into a downwardly inclined lip, a recovery cylinder located beneath the lip portion of the tray and having end flanges in rolling contact with the exterior periphery of the crushing cylinder, a recovery cylinder having its outer periphery in rolling contact with the opposite side of the crushing cylinder, a tray extending between the recovery cylinders to contact with the exterior periphery thereof to receive the ore from the flanged recovery cylinder to pass it to the point of contact between the crushing cylinder and the other of the aforesaid recovery cylinders, and means for feeding the ore crushed between the crushing cylinder and the recovery cylinder and into the interior of either of the recovery cylinders.

Dated at Prince Rupert, B. C., March 2nd, 1922.

ALEXANDER HALLIDAY.
